Friedrich LLP(57) **CLAIM**

The ornamental design for a rechargeable battery, as shown and described.

DESCRIPTION

FIG. 1 is a front, top, left perspective view of a rechargeable battery showing my new design;

FIG. 2 is a rear, top, left perspective view thereof;

FIG. 3 is a front elevational view thereof; and

FIG. 4 is a top plan view thereof.

FIG. 5 is a rear elevational view thereof;

FIG. 6 is a left side elevational view thereof;

FIG. 7 is a right side elevational view thereof; and,

FIG. 8 is a bottom plan view thereof.

The even-dash broken lines form no part of the claimed design. The dot-dash broken lines define the boundaries of, but not included in, the claimed design.
